CLAIM

The ornamental design for an urban bicycle helmet, as shown and described.

DESCRIPTION

A portion of the disclosure of this patent document contains material, which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a perspective view of an urban bicycle helmet showing my new design;

FIG. 2 is a front view of the urban bicycle helmet;

FIG. 3 is a rear view of the urban bicycle helmet;

FIG. 4 is a left side view of the urban bicycle helmet;

FIG. 5 is a right side view of the urban bicycle helmet;

FIG. 6 is a top view of the urban bicycle helmet; and,

FIG. 7 is a bottom view of the urban bicycle helmet.

The broken lines in the drawings represent portions of the urban bicycle helmet that form no part of the claimed design.
